UNITED STATES PATENT OFFICE.

GEORGE EDWARD FAUPEL, OF BEEVILLE, TEXAS.

RAZOR STROP.

Application filed May 2, 1923. Serial No. 636,220.

To all whom it may concern:

Be it known that I, GEORGE E. FAUPEL, a citizen of the United States, and resident of Beeville, in the county of Bee and State of Texas, have invented certain new and useful Improvements in Razor Strops, of which the following is a specification.

My invention relates generally to improvements in razor-strops, more particularly to improvements in razor-strops of that type of construction in which one or more straps are provided for use in sharpening razor blades or like cutting tools, and it consists in the combinations, constructions and arrangements herein described and claimed.

An object of the invention is to improve the construction of razor-strops of the type described in such manner as to provide the strop with means for regulating the moisture content of the strap or straps comprised in the strop, whereby the strap or straps will be kept in a satisfactory condition so far as the moisture content thereof is concerned, irrespective of the humidity of the atmosphere.

Other objects and advantages of the invention will be apparent from the following description, considered in conjunction with the accompanying drawings, in which—

30 Figure 1 is a fragmentary perspective view, showing a razor strop embodying the invention,

Figure 2 is a side elevation of the strop shown in Figure 1, with portions thereof broken away and other portions shown in section, and

Figure 3 is a transverse section through a moisture regulating element comprised in the strop exhibited in the preceding views.

40 In Figures 1 and 2 of the drawings, I show a razor strop including straps 1 and 2, each of which is attached at one end to a holder 3 having an attaching element 4, which may be a screw eye, hook or like element and which constitutes means for attaching the holder to a fixed support, not shown. With the arrangement shown, the straps 1 and 2 are supported in substantially superposed relation. The straps 1 and 2

50 may be formed with abrading surfaces differing in degree, as when the strap 1 is made of leather and the strap 2 of canvas or like fabric. The abrading surfaces on the straps 1 and 2 ordinarily are provided on the faces thereof which are remote from each other.

The parts described so far are ordinary in construction and form no part of my invention except in so far as they cooperate with the parts which will be hereinafter described.

With the construction described so far, it has been found in practice that the leather strap will be unsatisfactory for use in sharpening razors when the air is very dry since the abrading surface will be rough and dry. When the humidity is relatively great, the abrading surface of the leather strap is too moist to satisfactorily fulfill the purpose for which it is provided. The objectionable features just mentioned are even more marked in the case of the canvas strap. Canvas straps ordinarily included in razor strops of the type described are treated or impregnated with a starchy substance which causes them to swell when they become damp.

When the air is relatively dry, the canvas strap will become stiff and will have a rough surface. It is true that straps included in razor-strops and particularly the canvas straps are coated with paraffin or like substance for the purpose of giving the strap a smooth glossy surface and for preventing the strap from absorbing moisture. However, the paraffin coating on the strap is soon worn off in service and cannot be replaced thereon with success by any one not having special training in that work.

In carrying out my invention, I provide a humidifying element 5 which may comprise a plurality of superposed strips 6 formed of blotting paper or like absorbent material and encased within a thin casing 7 made of a fabric permeable by water, the superposed strips 6 and the casing 7 being secured together by rows of stitching 8 or in any other suitable known manner. The humidifying element 5 is interposed between the straps 1 and 2 and is attached at one end to the holder 3 in such manner as to be supported in flatwise contiguous relation to the adjacent faces of the straps 1 and 2.

From the foregoing description of the various parts of the device, the operation thereof may be readily understood. When the moisture content of the atmosphere is relatively great, the humidifying element 5 will absorb moisture from the straps 1 and 2 so that the latter will be kept in a satisfactorily moistened condition. The humidi-

fying element because of its construction will retain a relatively great amount of moisture and when the air is dry will supply sufficient moisture to the straps to keep them 5 in a satisfactory condition.

Obviously, my invention is susceptible of embodiment in forms other than that illustrated in the accompanying drawings and I therefore consider as my own all modifications and adaptations of the form of the 10 device herein disclosed which fairly fall within the scope of the appended claim.

Having thus described the invention, what I claim is:—

In a razor strop, a plurality of straps and 15 an elongated humidifying element interposed between adjacent straps, the humidifying element comprising a plurality of superposed strips formed of an absorbent material, a fabric casing for the superposed strips and stitching securing the casing and the strips together. 20

GEORGE EDWARD FAUPEL.
